TOY ANIMAL FIGURE

Margaret Hockaday, New York, N. Y.

Application March 21, 1956, Serial No. 40,715

Term of patent 7 years

(Cl. D34—2)

Fig. 1 is an elevational view of a toy animal figure, embodying my new design; and

Fig. 2 is an edge view of the same.

The other side and other edge of the figure are substantially identical with the side and edge shown.

I claim:

The ornamental design for a toy animal figure, substantially as shown and described.
